UNITED STATES PATENT OFFICE.

FRANK L. GORMLEY, OF BOSTON, MASSACHUSETTS.

LIFTING-JACK.

933,704.

Specification of Letters Patent. Patented Sept. 7, 1909.

Application filed February 15, 1909. Serial No. 478,305.

To all whom it may concern:

Be it known that I, FRANK L. GORMLEY, a citizen of the United States of America, and a resident of Boston, in the county of Suffolk and State of Massachusetts, have invented certain new and useful Improvements in Lifting-Jacks, of which the following is a specification.

This invention relates to lifting jacks and particularly to that class of jacks which are known as ratchet screw jacks, and has for its object the provision of a means whereby the movable member is prevented from being accidentally lowered under a heavy load.

The invention consists in interposing between the gear keyed to the lifting screw and the inner face of the movable member two plates separated by means of a plurality of anti-friction members with their outer faces respectively in contact with the gear upon the lifting screw and the inner face of the movable member, these two plates being connected together by some device such as a plurality of ratchet teeth upon one plate and a pawl upon the other plate whereby the plates are free to move about the axis of said lifting screw independently of one another in one direction while they will be obliged to move simultaneously in the opposite direction.

The invention consists in certain novel features of construction and arrangement of parts which will be readily understood by reference to the description of the drawings and to the claims hereinafter given.

Of the drawings: Figure 1 represents a horizontal section of a lifting jack embodying the features of this invention, the cutting plane being on line 1—1 on Fig. 2. Fig. 2 represents a vertical section of the same, the cutting plane being on line 2—2 on Fig. 1. Fig. 3 represents an elevation of the friction devices interposed between the inner face of the movable member and the lifting screw gear. Fig. 4 represents an inverted plan of the annular pawl carrying plate, and Fig. 5 represents a plan of one of the friction disks.

Similar characters designate like parts throughout the several figures of the drawings.

In the drawings, 10 represents a suitable base supporting a stationary standard 11 over the outer periphery of which is fitted

a movable sleeve 12, to the upper end of which is threaded a head 13. In the upper end of the standard 11 is mounted a nut 14 to which is threaded a lifting screw 15 having splined to its upper reduced end a gear 16 with which meshes a gear 17 formed upon 60 or secured to a revoluble shaft 18, the outer end of which is provided with a suitable operating mechanism 19 of any well-known construction.

Interposed between the upper face of the gear 16 and the inner face of the movable member 12 are two annular plates 20 and 21 between which are interposed a plurality of anti-friction members 22. Between the plate 20 and the inner face of the movable member 12 is a friction disk 23 and between the annular plate 21 and the upper face of the gear 16 is a similar friction disk 23. The plate 21 is provided with a plurality of upwardly extending ratchet teeth 24 with 75 which engage the pawls 25 pivotally mounted on the annular disk 20 and forced downwardly into engagement with said teeth 24 by means of suitable springs 26.

It is obvious that when the handle 19 is 80 operated to move the gear 16 in the direction of the arrow indicated on Fig. 1 of the drawings the screw 15 will be so turned in the nut 14 as to cause the member 12 to be lifted relative to the standard 11 and during 85 this rotation of the gear 16 the friction between the plate 21 and said gear 18 caused by the interposition of the friction disk 23 will be such as to cause the plate 21 to rotate with said gear, the teeth 24 thereon 90 freely passing the pawl 25 without causing any rotation of the disk 20.

It is obvious that if the load is light the gear 16 might revolve independently of the plate 21 without altering the principles of 95 this invention. When an extra heavy load, however, is supported by the member 12 there is a tendency caused thereby owing to the coarse pitch of the screw 15 to turn in the nut 14. Owing to this extreme weight, 100 any tendency of the screw 15 to turn in the reverse direction will rotate with it the gear 16 and owing to the friction between this gear and the plate 21 cause this plate to simultaneously rotate therewith. In rotating 105 in this manner the teeth 24 will engage with the pawls 25 pivotally mounted upon the plate 20 and owing to the abnormal friction

between this plate 20 and the inner face of the movable member 12 the turning of the screw 15 will be wholly prevented or limited to such an extent as to prevent any accident.

5 It is obvious that the accidental lowering of the movable member of the lifting jack is very dangerous and obviously objectionable and it is self-evident that by means of the construction herein shown and described 10 that this objection is wholly removed.

It is believed that from the foregoing the operation and many advantages of the invention will be fully understood.

Having thus described my invention, I 15 claim:

1. In a lifting jack, the combination of a stationary member; a movable member thereon; a screw for said movable member; means for rotating said screw; a plate carried by 20 said screw; a plate carried by said movable member; a plurality of anti-friction members interposed between said plates; and means for connecting and disconnecting said plates to insure the simultaneous movement 25 of said plates in one direction while permitting the independent movement of one of said plates in the opposite direction.

2. In a lifting jack, the combination of a stationary member; a movable member thereon; a screw for said movable member; means for rotating said screw; a plate carried by 30 said screw; a friction disk interposed between said plate and said screw; a plate carried by said movable member; a plurality of anti-friction members 35 interposed between said plates; and means for connecting and disconnecting said plates to insure the simultaneous movement of said plates in one direction while permitting the independent 40 movement of one of said plates in the opposite direction.

3. In a lifting jack, the combination of a stationary member; a movable member thereon; a screw for said movable member; means 45 for rotating said screw; a plate carried by said screw; a plate carried by said movable member; a friction disk interposed between said plate and said movable member; a plurality of anti-friction members 50 interposed between said plates; and means for connecting and disconnecting said plates to insure the simultaneous movement of said plates in one direction while permitting the independent movement of one of said plates in 55 the opposite direction.

4. In a lifting jack, the combination of a stationary member; a movable member thereon; a screw for said movable member; means for rotating said screw; a plate carried by 60 said screw; a friction disk interposed between said plate and said screw; a plate carried by said movable member; a friction disk interposed between said plate and said movable member; a plurality of anti-friction 65 members interposed between said plates;

and means for connecting and disconnecting said plates to insure the simultaneous movement of said plates in one direction while permitting the independent movement of one of said plates in the opposite direction. 70

5. In a lifting jack, the combination of a stationary member; a movable member thereon; a screw for said movable member; means for rotating said screw; a plate carried by 75 said screw; a friction disk interposed between said plate and said screw; a plate carried by said movable member; a friction disk interposed between said plate and said movable member; a plurality of anti-friction members 80 interposed between said plates; and a device secured to one of said plates and engaging the other for connecting and disconnecting said plates to insure the simultaneous movement of said plates in one direction while permitting the 85 independent movement of one of said plates in the opposite direction.

6. In a lifting jack, the combination of a stationary member; a movable member thereon; a screw for said movable member; means for rotating said screw; two plates 90 interposed between said movable member and screw, one of said plates being provided with a plurality of teeth and the other having pivoted thereto a pawl engaging said 95 teeth; and a plurality of anti-friction members interposed between said plates.

7. In a lifting jack, the combination of a stationary member; a movable member thereon; a screw for said movable member; means for rotating said screw; two plates 100 interposed between said movable member and screw, one of said plates being provided with a plurality of teeth and the other having pivoted thereto a pawl engaging said teeth; and a friction disk interposed between each plate and the member 105 with which it coöperates.

8. In a lifting jack, the combination of a stationary member; a movable member 110 thereon; a screw for said movable member; means for rotating said screw; two plates interposed between said movable member and screw; and means for connecting and disconnecting said plates to permit one of 115 them to rotate independently in one direction and insuring the rotation of both plates in unison in the opposite direction.

9. In a lifting jack, the combination of a stationary member; a movable member 120 thereon; a screw and nut for raising and lowering said movable member one of which is revolute; and a divided device interposed between the revolute member and said movable member and in frictional contact therewith adapted to permit said revolute member to rotate freely in one direction but prevent the accidental rotation thereof in the opposite direction under a heavy load. 125

10. In a lifting jack, the combination of 130

a stationary member; a movable member thereon; a screw for said movable member; a nut therefor; means for rotating said screw; and a divided friction device interposed between said screw rotating means and movable member and in frictional contact therewith adapted to permit said screw rotating means to revolve freely in one direction while its accidental rotation in the

opposite direction under a heavy load is prevented. 10

Signed by me at 4 Post Office Sq., Boston, Mass., this 28th day of January, 1909.
